UNITED STATES PATENT OFFICE.

JOHN I. NEWBURG, OF VICKSBURG, MISSISSIPPI.

HYDRAULIC MOTOR.

SPECIFICATION forming part of Letters Patent No. 703,451, dated July 1, 1902.

Application filed November 5, 1901. Serial No. 81,240. (No model.)

To all whom it may concern:

Be it known that I, JOHN I. NEWBURG, a citizen of the United States, residing at Vicksburg, in the county of Warren and State of Mississippi, have invented new and useful Improvements in Hydraulic Motors, of which the following is a specification.

My invention relates to improvements in motors, and contemplates the provision in either a hydraulic or a pneumatic motor of a wheel which, while capable of enabling a current of water or air to exert considerable leverage on and easily turn the shaft on which the wheel is carried and otherwise highly efficient in operation, is simple and compact in construction and embodies no parts that are liable to get out of order after a short period of use.

The improved wheel is designed more particularly for use in a hydraulic motor, and therefore will be described in conjunction with the same.

In the accompanying drawings, Figure 1 is a rear elevation of the motor embodying my improvements as it appears in its proper operative position in a running stream, and Fig. 2 is a vertical section taken in the plane indicated by the line 2 2 of Fig. 1.

In the said drawings similar letters of reference designate corresponding parts in both views, referring to which—

A A are two floats arranged parallel in the stream and at about the proportional distance illustrated apart, B B hangers connected to and depending from the floats and provided with suitable bearing-boxes a, and C the improved wheel mounted in the hangers and disposed between the floats, with its end presented to the current in the stream. The said wheel in the preferred embodiment of the invention is carried by a shaft b, journaled in the boxes a and equipped with a sprocket b' or other means for transmitting power, and it is preferably made up of parallel circular rims c, hubs d, fixed on the shaft by set-screws e or other suitable means, spokes f, interposed between and connecting the rims and the hubs, and four blades D, each of which is connected by bracket-arms g or other suitable means to both of the rims c, and by preference to the rims c alone, for a purpose which will be presently pointed

out. The bracket-arms g have curved end portions connected to the interior perimeters of the rims c, and they extend entirely across the blades, which are preferably formed by plates of sheet metal, whereby they are enabled to effect a very strong and durable connection of the blades to the rims and one calculated to withstand the great strain placed on the blades in practice.

In addition to each blade being attached to both rims c at its ends it will be seen that the edges of the blades are in planes parallel with that of the axis of the wheel, although the edges themselves are oblique as to the axis; also, that the blades are located at equal intervals about the shaft, with the result that the forward portion—i. e., the upstream portion—h of each rests in advance of the rear portion i of the one which precedes it with reference to the direction in which the wheel turns. From this it follows that with the wheel submerged in the stream, as shown in Fig. 1, the current acting against the entire area of the blade-faces presented to it will rotate the wheel in the direction indicated by arrow. It will also be observed that by virtue of the large surfaces which the faces of the blades present to the current and the leverage afforded by the described connection of the blades to the rims c alone of the wheel the current is enabled to easily rotate the shaft b and drive any machinery that may be connected therewith.

When desirable, a plurality of the wheels C may obviously be fixed on a common shaft without departing from the scope of my invention.

The improved wheel is designed, primarily, for use as a water-wheel; but as it possesses all of the advantages pointed out when employed as a wind-wheel I desire it distinctly understood that it may be employed as such; also, that the blades D may be of any suitable description, provided they are relatively arranged and connected to the wheel-rims, as described.

I have entered into a detailed description of the present and preferred embodiment of my invention in order to impart a full, clear, and exact understanding of the same. I do not desire, however, to be understood as confining myself to the specific construction and

relative arrangement of parts as described, as such changes or modifications may be made in practice as fairly fall within the scope of my claim.

5 Having described my invention, what I claim, and desire to secure by Letters Patent, is—

In the motor described, the combination of the shaft, the circular rims arranged one in 10 advance of the other around the shaft, connecting means interposed between the shaft and rims, and the four blades located at equal intervals about the shaft with their edges in planes parallel with that of the axis of the

wheel although said edges themselves are oblique as to the axis, and each attached to both of the rims at its ends, whereby the forward or upstream portion of each blade is disposed in advance of the rear portion of the blade which precedes it with reference to the direction in which the wheel is designed to turn.

In testimony whereof I have hereunto set my hand in presence of two subscribing witnesses.

JOHN I. NEWBURG.
